UNITED STATES PATENT OFFICE.

OSCAR NYGAARD, OF SAUGUS, MASSACHUSETTS, ASSIGNOR TO BERNITZ FURNACE APPLIANCE COMPANY, OF BOSTON, MASSACHUSETTS, A CORPORATION OF MASSACHUSETTS.

FIRE BRICK.

Application filed May 18, 1925. Serial No. 31,227.

This invention relates to fire brick and is especially concerned with brick designed to be used in the walls of furnaces which are subject to sustained operation at high temperatures. For example, in furnaces for water tube boilers when the fuel is supplied by underfeed stokers and forced draft is applied, the heat in the fuel bed becomes so intense that the slag, clinkers and ash fuse to the furnace lining, and when this fused mass is removed a part of the lining is chipped off with it. The action then repeats, with the result that the life of the lining is greatly reduced. It has been found that this difficulty can be obviated by admitting air into the fuel bed along the portion of the furnace wall where the clinker formation occurs, the air serving to cool the wall face below the fusing point. Also in modern boiler installations where pulverized fuel is used resulting in sustained operation at high temperatures it has been found advisable to utilize air passages through the furnace walls for the purpose of cooling the walls and prolonging their life.

The present invention is especially concerned with the construction of furnace walls where air passages are desirable and it is the chief object of the invention to devise a brick which will be particularly adapted for the requirements of such a wall.

The nature of the invention will be readily understood from the following description when read in connection with the accompanying drawings, and the novel features will be particularly pointed out in the appended claims.

Referring now to the drawings,

Figure 1 is a vertical cross sectional view of a brick embodying the present invention;

Fig. 2 is a front elevation of the rear section of the brick shown in Fig. 1;

Fig. 3 is a rear elevation of the front section of said brick;

Fig. 4 is a cross sectional view through a portion of a furnace showing a typical ventilated wall construction with a lining made of brick of the character shown in Fig. 1;

Fig. 5 is a front view of a portion of the wall shown in Fig. 4.

The brick shown comprises a front or facing section 2 and a rear or backing section 3. The front section is recessed, as

shown at 4, to receive a central projection 5 extending forwardly from the front of the rear section 3, and the front section also is provided with an internal shoulder 6 to limit the distance that the projection 5 can be forced into the recess 4. When these sections have been assembled in the relationship shown in Fig. 1 and secured together by a layer of cement 7, the two parts are united both adhesively and also through the mechanical interlocking of the sections. 65

The shoulder 6 not only limits the movement of the projection 5 into the recess 4, but it also spaces the end of this projection from the inner surface of the front section 2, and thus provides an air space or chamber 8 of substantial thickness and area between the central portions of the two sections. In other words, the marginal portions only of the two sections are united and the central areas of these parts are separated by the 75 air space 8. Preferably several air holes or passages 10 are formed through the front section 2 and corresponding holes 12, in alignment with the holes 10, are provided in the rear section 3. These holes preferably 80 are tapered to allow for the expansion of the air as it approaches the highly heated surface of the lining. Another hole 13 is formed centrally through the rear section and opens into the air space 8 in an offset 85 relationship to the holes 10.

It is contemplated that the front section 2 will ordinarily be made of some highly refractory material, preferably carborundum, while the rear section 3 will be made 90 of some relatively inexpensive and less refractory material, such as fire clay. For some purposes it may be satisfactory to make both sections of fire clay or of some other material having similar characteristics.

In a typical furnace, such for example, as that shown in Fig. 4, the furnace wall is made hollow; or, in other words, is provided with an air chamber 14, Fig. 4, immediately behind the furnace lining 15. Air under pressure is forced into the chamber 14 while the furnace is being operated, and this air flows through the holes 12 and 10 to the face of the lining. This materially 100 reduces the temperature of the lining. The lining is further cooled by the air which flows through the hole 13 into the air space 105

8, circulates through this space, and then mingles with the air that flows through the holes 10. While some circulation in the air space 8 undoubtedly would be produced if the hole 13 were omitted, I prefer to provide some means for establishing a more vigorous circulation of air through this space than would be produced simply by eddy currents created by air flowing through the 10 holes 10.

It will now be evident that this invention provides a brick for furnace linings which is particularly well adapted to withstand high temperatures, while at the same time being so constructed that it can be manufactured very economically. The fact that the front or facing section is relatively thin facilitates the conduction of heat through the lining to the air space, from which it is 15 swept away by the continuous circulation of air. Excessive heating of the furnace lining thus is prevented.

While I have herein shown and described the best embodiment of my invention that I 20 have so far devised, it is contemplated that the invention may be embodied in many other forms without departing from the spirit or scope thereof. For example, various arrangements of air passages may be 25 used.

Having thus described my invention, what I desire to claim as new is:

1. A fire brick comprising front and rear sections of refractory material with their 30 marginal portions secured together and their central portions separated from each other by an air space of substantial area, said rear section having one or more air passages extending therethrough and opening into said 35 air space.

2. A fire brick comprising front and rear sections of refractory material with their marginal portions secured together and their central portions separated from each other 40 by an air space of substantial area, said sections each having a plurality of air conducting holes formed therethrough substantially in alignment with each other, and the rear section having an additional hole opening 45 into said air space and offset with reference to the holes in said front section.

3. A fire brick comprising front and rear sections of refractory material secured together with an air space separating said sections throughout a large part of their areas, and each of said sections having an air hole 55 formed therethrough and opening into said air space.

4. A fire brick comprising front and rear 60 sections of refractory material secured together with an air space separating said sections throughout a large part of their areas, and each of said sections having air holes 65 formed therethrough and opening into said air space, certain of the holes through said

rear section being in alignment with the holes through the front section, and an additional hole through said rear section communicating with said air space and out of alignment with the holes in the front section. 70

5. A fire brick comprising front and rear sections of refractory material having marginal portions interlocked with each other and their central portions separated from each other by an air space of substantial 75 area, the material of the front section being more refractory than that of the rear section, and said rear section having one or more air passages extending therethrough and opening into said air space. 80

6. A fire brick comprising front and rear sections of non-metallic refractory material interlockingly engaged at marginal portions but shaped to provide an air space of substantial area immediately behind the central portion of said front section, one of said sections having an air passage formed therethrough and opening into said air space. 85

7. A fire brick comprising front and rear sections of non-metallic refractory material 90 permanently attached to each other and shaped to provide an air chamber between them, said front section being of more refractory material than the rear section, and said brick having one or more air passages 95 opening into said air chamber.

8. A fire brick comprising front and rear sections of non-metallic refractory material, said sections being marginally interlocked with each other and said brick having therein an air space of substantial area immediately behind the central portion of said front section, a plurality of air holes extending from said space through said front section, and an air hole extending through said 100 rear section and opening into said space, said front section being made of more refractory material than the rear section. 105

9. A fire brick comprising front and rear sections of nonmetallic refractory material 110 marginally interlocked with each other and shaped to provide an air chamber between them, said front section being of more refractory material than the rear section and said brick having one or more air passages 115 opening into said air chamber.

10. A fire brick comprising front and rear sections of nonmetallic refractory material having marginal portions interlockingly engaged and shaped to provide an air chamber 120 therebetween, said brick having one or more air passages opening into said air chamber.

11. A fire brick comprising front and rear sections of nonmetallic refractory material 125 permanently attached to each other and shaped to provide an air chamber therebetween, and said brick being constructed to cause a circulation of air through said chamber.

12. A fire brick comprising front and rear 130

sections of refractory material permanently attached to each other and shaped to provide an air chamber therebetween and said brick having passages therethrough arranged to circulate air through said chamber.

13. A furnace wall formed of front and rear sections, said front section comprising

fire brick having front and rear sections of nonmetallic refractory material interlocked with each other and shaped to provide an air chamber between the sections of brick, said bricks each having one or more air passages opening into said air chamber.

OSCAR NYGAARD.
